ADJUSTABLE SUSPENSION DEVICE FOR CEILING PANELLINGS

Ove Andreas Jørgensen, 54 Østrupvej, Odense, Denmark
Filed June 7, 1960, Ser. No. 34,536
Claims priority, application Great Britain June 15, 1959
1 Claim. (Cl. 248—327)

This invention relates to an adjustable suspension device for ceiling panellings. Such panellings may have a purely ornamental purpose but may also have sound-deadening properties or may form a support for sound-quenching material, such as bats of mineral wool.

The panelling proper may consist of elements of elongated or some other appropriate shape which are made from thin sheet material, such as finely perforated or non-perforated aluminum sheet. In many cases such panelling elements are nailed or otherwise secured directly to the ceiling surface but in other cases it is desired to suspend the panelling at some distance below the ceiling surface, e.g., in order to provide a hidden space above the paneling in which the coils of a heating and/or cooling system or the air supply conduits of a ventilation system may be installed. In the latter case, the elements of the panelling may be releasably supported by a plurality of carrying rails which are suspended at some distance below the ceiling surface. It is usually of particular importance that the surface of the finished panelling is accurately plane and, accordingly, the carrying rails of the panelling have to be exactly in level with each other.

It is known to suspend the carrying rails by means of looped wires of steel or other metal material, the length of the loops of which may be varied in order to adjust the effective length of the wires. However, it is rather difficult to obtain the desired accuracy in this way because the effective length of a wire may change unintentionally when the knot of the wire loop is tightened.

According to the present invention, an adjustable suspension device for ceiling panellings comprises an upper strap portion intended to be secured to a ceiling, and a lower strap portion intended to be secured to a carrying rail of the panelling, the lower and upper ends, respectively, of said strap portions in their operative position overlapping each other and being clamped together by means of a toggle clamp, the lever of which is journaled in one of said strap portions. When using such suspension devices which are relatively cheap in manufacture, it is extremely easy to adjust the effective length of the device with a high degree of accuracy so that the time required for the manual work of mounting the paneling is reduced to a minimum.

In a preferred embodiment of the invention the strap portions are of band formation and have substantially the same width, one of the strap portions being provided with opposed up-turned flanges along its longitudinal edges to form lateral guides for the other strap portion, and said flanges having apertures in which the toggle clamp lever is journaled. Such devices may be manufactured at low costs by means of automatic or semi-automatic machines and will be able to guarantee a very reliable suspension of carrying rails and the panelling elements.

The invention will now be more fully described with reference to the accompanying drawings, in which—

FIG. 1 shows a sectional elevation of a portion of a carrying rail and one of its suspension devices, portions of the panelling proper being indicated in dotted lines, and

FIG. 2 a transverse section taken substantially along the line II—II in FIG. 1.

2

In the embodiment illustrated on the drawings, the panelling proper comprises a plurality of parallel elongated elements 1, shown in dotted lines. Each of these elements is of channel formation and comprises a laterally extending flange 2. 3 designates a portion of a carrying rail extending transversely to the longitudinal direction of the panelling elements 1. Also the carrying rail 3 is of channel formation, and in the bottom portion 4 thereof a series of hooks 5 are stamped out for supporting the elements 1. Adjacent each hook 5 the bottom portion 4 of the carrying rail 3 further comprises a downwardly extending lug 6 which forms a stop for the free edge of the lateral flange 2 of the particular element 1 when this element is being mounted.

10 The carrying rail 3 is suspended from the ceiling, not shown, by means of a plurality of suspension devices, each of which comprises an upper strap portion 7 and a lower strap portion 8. By means of a screw or the like, not shown, the upper strap portion 7 may be secured to the ceiling, and by means of another screw connection comprising a headed screw 9 and a nut 10, the extreme lower end 11 of the lower strap portion 8 may be secured to the bottom portion 4 of the carrying rail 3.

15 Both strap portions 7 and 8 are of band formation and have substantially the same width. In the embodiment shown the lower strap portion 8 is provided at its upper end with a pair of opposed side flanges 12 which form lateral guides for the upper strap portion 7, and in which a pair of opposite apertures 13 are stamped out.

20 In these apertures 13 a pair of opposite lateral ears 14 on the short arm 15 of a toggle clamp lever 15, 16 are received. The short arm 15 has substantially the same width as the strap portions 7 and 8 whereas a portion of the longer arm 16 has a greater width, see FIG. 2, 25 so that this longer arm in the locking position of the clamp may rest against the edges of the flanges 12, 12 as illustrated in the drawing. In this position the strap portions 7 and 8 are clamped together by means of the toggle clamp 15, 16, and by appropriate dimensioning of the elements of the suspension device it is possible to obtain a very firm engagement between the strap portions 7, 8 so that the effective length of the device, and thus the spacing of the carrying rail 3 below the ceiling surface, will not change unintentionally. On the other hand, the engagement because of the resiliency of the elements of the suspension device between the strap portions 7 and 8 may easily be relieved by merely swinging the toggle lever 15, 16 in anti-clockwise direction. After such release the effective length of the suspension device 30 may be varied at will.

35 It will be appreciated that the invention is not restricted to the embodiment illustrated in the drawing. By way of example, the toggle clamp lever may be carried by the upper strap portion 7, and the suspension device may 40 be secured to the ceiling and to the carrying rail in many ways different from that illustrated in the drawing. Thus, when the carrying rails are of tubular formation, it may be advantageous to use upper strap portions of band material and lower strap portions of wire material that 45 is bent around the carrying tube. In this case the toggle clamp may be provided at the lower end of the upper strap portion, and the end of the shorter toggle clamp lever 15 may have a recess 17, FIG. 2, to receive the upper end portion of the wire.

50 I claim:

55 In a ceiling panelling comprising a plurality of parallel elongated panelling elements and a number of carrying rails extending in the transverse direction of said elements, means for releasably connecting said elements to

said carrying rails, and adjustable suspension means comprising a plurality of upper strap members each having an upper end fixed and extending downwardly from its upper end towards the carrying rails and a plurality of lower strap members having their lower ends connected to the carrying rails and extending upwardly therefrom and having their upper ends overlapping the lower ends of the upper straps, and a toggle clamp lever journaled in one of said strap members and operative to clamp said overlapping end portions together in any adjusted position.
